UNITED STATES PATENT OFFICE.

HIRAM WILBER HUBBARD, OF MILWAUKEE, WISCONSIN, ASSIGNOR OF THREE-FIFTHS TO LOGEMANN BROTHERS COMPANY, OF MILWAUKEE, WISCONSIN, A CORPORATION OF WISCONSIN.

CONCRETE-MIXER.

No. 820,928.

Specification of Letters Patent.

Patented May 15, 1908.

Application filed June 20, 1904. Serial No. 213,205.

To all whom it may concern:

Be it known that I, HIRAM WILBER HUBBARD, residing in Milwaukee, in the county of Milwaukee and State of Wisconsin, have invented new and useful Improvements in Concrete-Mixers, of which the following is a description, reference being had to the accompanying drawings, which are a part of this specification.

10 This invention relates to improvements in concrete-mixers, and has for its object to provide means for thoroughly mixing the ingredients for the preparation of concrete for any of the usual purposes.

15 Another object of this invention is to provide such a mechanism that will operate continuously, receiving a constant supply of materials and discharging steadily the completed homogeneous mixture thereof.

20 Another object of this invention is to provide a continuously-operating concrete-mixer with a novel means for introducing water to the material at an intermediate portion of the machine, such means being protected 25 from the action of the said material.

Another object of this invention is to accomplish the above result by the employment of a pair of conical drums, one projecting within the other, so as to provide a space between them to contain the water-injecting 30 means.

Another object of this invention is to equalize the pressure upon the supporting-frame by employing a pair of mixing-drums rotating in opposite directions.

40 Another object of this invention is to provide for adjustably determining the speed of travel of the material through a mixer-drum with relation to the speed of rotation of the drum.

With the above and other objects in view the invention consists in the devices and parts and their equivalents, as hereinafter set forth.

Referring to the accompanying drawings, 45 in which like characters of reference indicate the same parts in the several views, Figure 1 is a vertical longitudinal sectional view of a concrete-mixer embodying this invention. Fig. 2 is an end elevation of the lower drum thereof looking in the direction of the axis of said drum. Fig. 3 is a diagram showing the course of the materials through the drum. Fig. 4 is a plan view of a supporting-frame

somewhat similar to that shown in Fig. 1, but slightly modified therefrom; and Fig. 5 is an 55 end elevation of the two drums as shown in Fig. 1 looking in a horizontal direction and showing the lower drum sectioned on the line 55 of Fig. 1 and illustrating the action of the drum-blades upon the material. 60

In these drawings, 8 represents an inclined supporting-frame which is preferably rectangular and constructed of channel-iron sides and I-beam cross-rails, as shown. The supporting-frame is mounted on wheels 9 to constitute a vehicle in the usual manner, the front wheels being omitted in the illustration. 65

Suitable journal-boxes 10 are arranged on the cross-beams of the frame near each side 70 thereof, and journaled in them are shafts 11 in pairs arranged in alinement. Friction-rollers 12 are fixed on the shafts 11 at each end thereof and fit against the bearings 10 to form thrust-bearings for the shafts 11. 75

A metal drum 13, formed of a hollow shell shaped like a truncated cone, is mounted on the friction-rollers 12 of the upper pair of shafts 11 by having securely fastened within its larger end a slightly-reduced mouth-ring 80 14, which has a shouldered annular track 15 bearing on the upper friction-rollers of the upper pair of shafts 11, and a collar 16, rigidly secured to the exterior of the shell near its smaller end, is provided with an annular 85 flanged rail 17 bearing upon the lower friction-rollers 12 of the upper pair of shafts 11.

A correspondingly-shaped drum 13' is similarly mounted upon the friction-rollers 12 of the lower pair of shafts 11 and is identical in 90 construction with the mixing-drum 13, with the exception that it is provided at its smaller or discharge end with a flaring rim 18. The lower drum 13' is so positioned that its mouth-ring 14' surrounds the smaller 95 end of the upper drum for a short distance, leaving an intervening space 19.

Within the space 19 between the overlapping ends of the two drums projects a water-supply pipe 20, having an arc-shaped perforated-spray-nozzle 21 following said space 19 to the bottom of drum 13, where it is provided with a drain-plug 22, threaded in its end. 100

Each of the mouth-rings 14 and 14' is provided with an annular series of gear-teeth 23 105

and 23', respectively, and a horizontal shaft 24, which is journaled lengthwise of the frame in suitable bearings 25, supported by the cross-beams of the frame, carries at its rear end a beveled pinion 26 to mesh with the gear-teeth 23' of the drum 13', and also carries a pinion 27 at its intermediate portion to mesh with an idle pinion 28, journaled on a stud 34, which is carried by a bearing 25 above the shaft 24 and which idle pinion in turn meshes with the gear-teeth 23 of the drum 13. The shaft 24 is driven by any suitable source of power (not shown) and by means of the pinions 26 and 27 rotates the mixing-drums, and by reason of the idle pinion 28 being interposed between the pinion 27 and the gear-teeth 23 of the drum 13 said drum will be caused to rotate in the opposite direction to the direction of rotation given to drum 13', as indicated by the arrows in Figs. 1 and 5.

Each of the mixing-drums is provided in the interior of its shell with longitudinal radial metal blades 29, which serve to lift the material contained within the mixing-drums during the rotation of said drums and carry it until the incline of said blades, due to their rotary motion, drops the material to other blades beneath or to the bottom of the drum, as clearly shown in Fig. 5, and thereby effects a thorough mixing of the several ingredients which are to constitute the concrete.

The material is fed to the upper drum through a hopper 30, which discharges into an inclined chute 31, entering the mouth of the upper drum, so that as the hopper is supplied with the dry ingredients they will pass by way of chute 31 into the drum 13 and there be thoroughly mixed by the lifting and dropping operation of the blades 29, and as the dry mixture falls from the smaller end of the upper drum 13 into the larger end of the lower drum 13' it has water sprayed into it from the nozzle 21, which being between the overlapping ends of the two drums is protected from contact with the falling material. The operation of the lower drum 13' is to thoroughly mix the water with the dry mixture received from the upper drum.

It is desirable that the lower edge of each mixing-drum should be perfectly horizontal, as shown in Fig. 1, and the incline of the frame 8 is designed to produce this effect when the wheels thereof rest upon a horizontal surface. The lower edge of a conical drum being horizontal, its axis is necessarily on an incline and the circle of rotation of any point of the drum is in an inclined plane at right angles thereto. The material falling from the chute 31 into the bottom of the drum is carried upward by the blades for a distance, moving in an inclined plane at right angles to the axis of the drum until it drops from the blades owing to the inclination of 65 said blades, and falling in a vertical line it

strikes the bottom of the drum at a point in advance of its starting-point, and this action is continued repeatedly, as indicated by the line *y* in the diagram of Fig. 3, until it is finally moved step by step throughout the 70 length of the drum and is discharged at the smaller end thereof. As a matter of fact the dropping of the material from the blades is not in the vertical line; but by reason of the longitudinal inclination of the blades at the 75 time the material slides therefrom it is given a forward start as it rolls across the blades to make it take a downward course inclined in the direction of the feed, and therefore adds to the progress of the feed. 80

Should it be found that in a particular instance the feed of the material through the drums is too rapid for a perfect admixture thereof, the said drums are to be adjusted so as to diminish the inclination of their axes 85 by any suitable means, such as by forcing wedge-blocks 32 beneath the rear wheels of the machine. Thus by making the axes of the drums nearer horizontal the planes of the lift of the material, which are at right angles to the axes, become nearer vertical, and consequently the pitch of the feed of said material is diminished and the time during which the material is retained within the drums is increased, so that a greater mixing 95 action is obtained to overcome such deficiency.

It is obvious from the above that an increased speed of feed may be accomplished by altering the inclination of the machine in 100 the opposite direction by the use of the wedge-blocks 32 or in any other desirable manner.

It will be observed that the treads of track-ring 16 and the track 15 are of the 105 same diameter, and consequently receive an even frictionless bearing on the pairs of equal-sized friction-rollers 12 on the parallel shafts 11, and the flange of the track-ring 16 and the shoulder of the track 15 by engaging the rims of said friction-rollers serve as thrust-bearings to prevent longitudinal displacement of the drum. Should it be found, however, that additional provision is necessary to prevent the thrust of the drums, 110 friction-rolls 33 may be provided with support from the cross-beams of the frame 8, as seen in Fig. 4, to bear against the flanges of the track-rings.

The open end of the lower drum serves as 115 a convenient means for viewing the mixing operation, so that an attendant may control the supply of water to suit the requirements of the condition of the mixture.

It is to be noted that aside from the provision of the convenient space 19 for the housing of the water-feed pipe the arrangement of the communicating pair of drums further enables the weight of the machine to be equally distributed on the two sides of the 120 130

frame by gearing the drums to rotate in opposite directions.

While the present invention is herein shown and described as applied to concrete-mixers, it is obvious that the novel principles involved are equally applicable to machines for other purposes, as in driers and in other classes of mixers, and therefore it is to be understood that such embodiments of these principles are to be included within the scope of my invention.

An important feature of this invention is that all of the blades of each mixing-drum are perfectly straight throughout and lie in axial planes which facilitates the manufacture of the machine and renders it comparatively easy of cleaning.

What I claim as my invention is—

1. In a device of the character described a mixing-drum comprising a conical shell, a track-ring mounted on the exterior of the shell and provided with a flanged tread, a reduced mouth-ring secured to the larger end of the shell and provided with a shouldered track, a supporting-frame, parallel shafts journaled in said frame, friction-rollers carried by the parallel shafts and receiving the tread of the track-ring and the track of the mouth-ring and bearing upon the flange of the track-ring and the shoulder of the mouth-ring, and means for rotating the drum.

2. In a device of the character described a mixing-drum comprising a conical shell, a track-ring mounted on the exterior of the shell and provided with a flanged tread, a reduced mouth-ring secured to the larger end of the shell and provided with a shouldered track, a supporting-frame, parallel shafts journaled in said frame, friction-rollers carried by the parallel shafts and receiving the tread of the track-ring and the track of the mouth-ring and bearing upon the flange of the track-ring and the shoulder of the mouth-ring, gear-teeth arranged around the mouth-ring, a drive-shaft journaled in the frame, and a pinion driven by the drive-shaft and meshing with the gear-teeth of the mouth-ring.

3. In a device of the character described an inclined frame mounted on wheels, a pair of conical mixing-drums rotatably mounted thereon and having their ends overlapping, each drum provided with a track-ring on its exterior having a flanged tread and a reduced

mouth-ring having a shouldered track with a series of gear-teeth, parallel shafts journaled in the frame, friction-rollers mounted on the parallel shafts and bearing on the tread and rail of the track-ring and mouth-ring respectively of each mixing-drum, a drive-shaft journaled in the frame, a pinion on the drive-shaft meshing with the gear-teeth of the lower drum, a second pinion on the drive-shaft, and a third pinion suitably journaled in the frame and meshing with the second pinion and the gear-teeth of the upper mixing-drum.

4. In a device of the character described, a pair of conical drums arranged on the same inclined axis with the smaller end of one drum projecting within the larger end of the other drum, and straight radial blades in the drums adapted to mix material and feed it through the drums by degrees by lifting the material carrying it forwardly and dropping it in an advanced position.

5. In a device of the character described, an inclined frame, a pair of conical drums rotatably mounted thereon with one drum having its smaller end projecting within the larger end of the other drum, means mounted on said frame for rotating the drums in opposite directions, and straight radial blades in the drums adapted to mix material therein and feed it through the drums by lifting the material and dropping it in an advanced position, the material being given a forward start by the inclination of the blades when it drops therefrom.

6. In a device of the character described, an inclined frame, a pair of conical drums rotatably mounted thereon arranged with their axes on an incline and the smaller end of one drum projecting within the larger end of the other drum with a space therebetween, means for rotating the drums, water-introducing means in said space between the drums, and straight radial blades in the drums for mixing material therein and feeding it therethrough by degrees, said blades lifting the material and dropping it in an advanced position.

In testimony whereof I affix my signature in presence of two witnesses.

H. WILBER HUBBARD.
